UNITED STATES PATENT OFFICE.

FRANK C. EMRICK, OF KALAMAZOO, MICHIGAN.

FELTING MACHINE.

Application filed October 21, 1922. Serial No. 595,962.

To all whom it may concern:

Be it known that I, FRANK C. EMRICK, a citizen of the United States, residing at the city and county of Kalamazoo, State of Michigan, have invented certain new and useful Improvements in Felting Machines, of which the following is a specification.

This invention relates to improvements in felting machines.

10 The main objects of the invention are:

First, to provide an improved felting machine which may be very successfully used for the felting of various materials and produces a superior product of uniform gage and density.

Second, to provide an improved felting machine adapted for producing material of various gages of any desired length.

Third, to provide an improved felting machine which is of very large capacity.

Fourth, to provide an improved felting machine which is simple in structure and requires very little attention and skill on the part of the operator.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing, forming 35 a part of this application, in which:

Fig. I is a rear elevation partially in vertical central section of a structure embodying the features of my invention, the delivery conveyor and table being removed.

40 Fig. II is a side elevation, the parts being broken away for convenience in illustration.

Fig. III is an enlarged detail section on a line corresponding to line 3—3 of Fig. II, showing details of the felting wheel and of 45 the manner of providing a packing for the felting wheel.

Fig. IV is an enlarged detail section on a line corresponding to line 4—4 of Fig. I, showing further details of the felting wheel and the packing.

50 Fig. V is a detail section of a modified form of my improved felting machine, the machine being especially designed for the manufacture of cylindrically curved articles such as coverings for pipes and the like.

In the drawing similar reference numerals

refer to similar parts throughout the several views and the sectional views are taken looking in the direction of the little arrows at the ends of the section lines.

60 Referring to the drawing, I provide a pair of pedestals 1 supporting the shafts 2 and 3 for the felting and pressing wheels. The felting wheel, designated generally by the numeral 4, comprises suitable spiders 5, the shaft 2 being stationary, the spiders having bearings 6 on the shaft. These spiders carry a peripheral perforated rim 7 supporting the felting screen 8. A gear 9 is secured to the felting wheel and meshes with a gear 10 on the shaft 3.

65 The press wheel 11 is made up of suitable spiders and a solid rim. The stock tank 12 has an opening in one side, the felting and pressing wheels being arranged in this opening to constitute the side of the stock tank, the side walls being conformed to these openings.

70 Packings 13 are arranged in the side walls 14 of the tank, see Fig. III, to coact with the ends of the felting and pressing wheels. Packings 15 are arranged in the top and bottom edges of the tank, see Fig. IV, to coact with the periphery of the felting wheel and the press wheel. These packings 15 are yieldingly supported by the springs 16. The stock is introduced to the tank 12 through the supply pipe 17. An air pipe 18 is provided at the bottom of the tank so that in the event of the machine being stopped with stock therein air may be introduced to accommodate the settled material or in the event that there should be a tendency for the material to settle air is introduced to accommodate the stock and 75 keep it uniformly distributed in its suspending water. The felt is delivered upon the surface of the felting wheel, the water passing therethrough and discharging to suitable drains, not illustrated. As the 80 wheel revolves the desired thickness of material accumulates thereon, the speed of the felting wheel being governed according to the percentage of felting material in the carrying or suspending liquid.

85 I provide a driving means 19 provided with a governor 20, the engine being connected with the driving shaft 21 connected by the worm 22 and gears 23 and 24 to the gear 10. A gaging screw 25 carried 90 by the arm 26 on the rock-shaft 27 is arranged to rest upon the felt carried by 95

the felting wheel at a point adjacent the bite of the felting and press wheels. The shoe and its supporting arm are shown by dotted lines in Fig. II.

- 5 On the outer end of the rock shaft is an arm 28 connected by the link 29 to the governor 20, the gaging screw thus controlling the governor and thereby the speed of the wheel enables the producing of felt 10 of substantially uniform gage. At the rear of the point of engagement of the felting and pressing wheels is a take-off table 30 which delivers to a conveyor 31. A suction box 32 is associated with this conveyor to remove some of the moisture from the felting.

To free the felting from the felting wheel I provide an air blast nozzle 33 which is directed so that the air is delivered substantially at the pressing point and at the rear thereof. This effectively loosens or frees the felt so that it passes on to the take-off table. The nozzle is mounted on the shaft 2 which is hollow and provided with 25 a connection 34 to a source of air supply.

In the modification shown in Fig. V the screen for the felting wheel 36 is concaved while the periphery of the coacting press wheel 37 is convexed to correspond. This 30 enables the manufacture of felting of circular cross section adapting it for use in covering conduits and the like.

My improved felting machine is well adapted for use in the manufacture of felt 35 from various kinds of material. It is of large capacity and requires but little attention on the part of the operator.

Having thus described my invention, what I claim as new and desire to secure by Letters Patent, is:

1. In a felting machine, the combination of a stock tank open at one side, a felting wheel provided with a peripheral felting screen, a coacting press wheel, said felt- 45 ing and pressing wheels being arranged in the said side opening of said stock tank to constitute a wall therefor, a take-off table disposed at the rear of the bite of said wheels, an air nozzle disposed within said 50 felting wheel to discharge a blast of air against the inside of the screen for disengaging the felted material therefrom, a driving means for said felting and pressing wheels including a governor, a rock shaft 55 having an arm thereon, a shoe on said arm resting on the felted material on the screen adjacent said press wheel, and operating connections from said rock shaft to said governor.

60 2. In a felting machine, the combination of a stock tank open at one side, a felting wheel provided with a peripheral felting screen, a coacting press wheel, said felt- 65 ing and pressing wheels being arranged in the said opening of said stock tank to consti-

tute a wall therefor, a take-off table disposed at the rear of the bite of said wheels, and an air nozzle disposed within said felting wheel to discharge a blast of air against the inside of the screen for disengaging the 70 felted material therefrom.

3. In a felting machine, the combination of a stock tank open at one side, a felting wheel provided with a peripheral felting screen, a coacting press wheel, said felting 75 and pressing wheels being arranged in the said side opening of said stock tank to constitute a wall therefor, packings disposed at the side edges of said tank opening to coact with the ends of said wheels and at 80 the top and bottom edges thereof to coact with the peripheries of said wheels, a take-off table disposed at the rear of the bite of said wheels, and an air nozzle disposed within said felting wheel to discharge a 85 blast of air against the inside of the screen for disengaging the felted material therefrom.

4. In a felting machine, the combination of a stock tank open at one side, a felting 90 wheel provided with a peripheral felting screen, a coacting press wheel, said felting and pressing wheels being arranged in the said opening of said stock tank to constitute 95 a wall therefor, a driving means for said felting and pressing wheels including a governor, a gaging member resting on the felted material on the screen adjacent said press wheel, and operating connections from said gaging member to said governor. 100

5. In a felting machine, the combination of a felting wheel provided with a peripheral felting screen, a coacting press wheel, means for delivering stock to said felting screen comprising a tank embracing one side of the wheel, a take-off table disposed at the rear of the bite of said wheels, an air nozzle disposed within said felting wheel to discharge a blast of air against the inside of the screen for disengaging the felted 110 material therefrom, a driving means for said felting and pressing wheels including a governor, a gaging member resting on the felted material on the screen adjacent said press wheel, and operating connections from said gaging member to said governor. 115

6. In a felting machine, the combination of a felting wheel provided with a peripheral felting screen, a coacting press wheel, means for delivering stock to said felting screen, a take-off table disposed at the rear of the bite of said wheels, and an air nozzle disposed within said felting wheel to discharge a blast of air against the inside of the screen for disengaging the felted material therefrom. 120

7. In a felting machine, the combination of a felting wheel provided with a peripheral felting screen, a coacting press wheel, means for delivering stock to said felting 125

screen comprising a tank embracing one side of the wheel, a driving means for said felting and pressing wheels including a governor, a gaging member resting on the felted material on the screen adjacent said press wheel, and operating connections from said gaging member to said governor.

8. In a felting machine, the combination of a felting wheel provided with a peripheral felting screen, means for delivering

stock to said felting screen comprising a tank embracing one side of the wheel, a driving means for said felting wheel including a governor, a gaging member resting on the felted material on the screen, and operating connections from said gaging member to said governor. 15

In witness whereof, I have hereunto set my hand and seal.

FRANK C. EMRICK. [L.S.]
